HERBERT W. CHENEY, OF MILWAUKEE, WISCONSIN, ASSIGNOR, BY MESNE ASSIGNMENTS, TO ALLIS-CHALMERS MANUFACTURING COMPANY, A CORPORATION OF DELAWARE.

MOTOR-DRIVEN COMPRESSOR.

1,172,581.

Specification of Letters Patent.

Patented Feb. 22, 1916.

Application filed May 15, 1912. Serial No. 698,024.

To all whom it may concern:

Be it known that I, HERBERT W. CHENEY, a citizen of the United States, residing at Milwaukee, in the county of Milwaukee and 5 State of Wisconsin, have invented a certain new and useful Improvement in Motor-Driven Compressors, of which the following is a specification.

This invention relates to motor driven 10 pumps or air compressors and has for its object the provision of such a motor driven compressor which is direct connected or devoid of the usual gearing, and which may run at very high speed, even as high as 1200 15 revolutions per minute, and which is greatly reduced in weight, width, and especially in height.

More particularly the invention relates to an inlet valve for compressors, and generally to details of construction of the motor compressor.

Comparing a usual form of motor driven compressor, such as that of Christensen Patent 635,280, Oct. 17, 1899, with the present machine of a capacity at least equal to 25 that of the Christensen type, the weight of the latter machine is 75 per cent. greater, the height is 70 per cent. greater, the width is 20 per cent. greater, while the length is 30 substantially the same as the corresponding weight and dimensions of the present machine. At a glance therefore, it is apparent that the present machine is substantially improved over machines of the prior art of 35 which the Christensen is a well known type.

The invention is illustrated in the accompanying drawings in the various figures of which like reference characters designate the same or similar parts.

40 Figure 1 is a plan view of the motor driven compressor, partly in section. Fig. 2 is an end elevation of the motor driven compressor, partly in section on the line II—II of Fig. 1, the view being taken 45 in the direction of the arrow indicated at the line II—II. Fig. 3 is a side elevation of the motor driven compressor viewed from the cylinder side thereof, some of the internal construction being shown in dotted 50 lines.

The frame of the motor driven compressor comprises generally three parts, the motor frame 1, the crank case 2, and the intermediate connecting piece 3. A clamping ring 4 abuts one end of the motor frame 1, while

a flange 5 on the connecting piece 3 abuts the opposite end of the motor frame 1, and bolts 6 connect together the clamping ring 4 and the flange 5 of the connecting piece 3, and clamp between them the motor frame 1. Bolts 7 connect the crank case 2 and the connecting piece 3. The motor frame 1, the crank case 2 and the connecting piece 3 are formed with surfaces of revolution at the places of coaction between these elements to facilitate the lining up of these parts when they are connected the one to the other. A motor cover plate 8 closes the end of the motor frame 1, while the crank case cover plate 9 closes a hand-hole opening in the crank case.

A series of cylinder supports 10 have integral therewith a base plate 11 and are connected by bolts 12 to an opening in the crank case opposite the hand-hole opening. 75 These cylinder supports 10 have formed integral therewith connecting portions 13, 14, of which one is located above the supports and constitutes a discharge conduit 140, while the other is located below the supports and constitutes a part of an inlet conduit or chamber 15. Straps 16, 16, bolted to the motor frame 1, and a strap 17 bolted to the crank case 2, are provided for bolting the motor driven compressor underneath 80 a car on which the device is provided.

The armature 18 on the motor is keyed to a taper portion 19 of a cranked armature shaft 20, and a nut 21 is threaded on the end of the taper portion 19 for holding the 90 armature in place on the said shaft. A part of the armature 18 is provided with screw threads 22 provided for coaction with screw threads on a cap, not shown, which is adapted to coat with the end of the shaft 20 for 95 the purpose of forcing the armature 18 off the taper portion 19 after first removing the nut 21. The clamping ring 4 furnishes a means for supporting the brushes of the motor, a support 23 being conventionally 100 shown.

The main bearing 24 for the cranked armature shaft 20 is formed in the connecting piece 3 and extends well into the armature 18. The only other bearing 201 for 105 the cranked armature shaft 20 is formed in the crank case 2, at an end thereof, beyond the cranked portions of the shaft. This bearing 201 is suitably supplied with oil through port 202. The main bearing 24 is 110

supplied with oil through a port 25, see Fig. 3, formed therethrough and through a bearing sleeve 26 held in the bearing 24. For the purpose of supplying this oil, a pocket 27 is formed in the connecting piece 3, which pocket opens directly into the chamber within the crank case 2. The bearing sleeve 26 is formed at its inner end with a groove 28 connecting with a conduit 29 formed in the connecting piece 3 and draining back into the chamber of the crank case 2. Oil throwers 30, 30, formed on the armature 18 lie opposite grooved chambers 31, 31, formed in the connecting piece 3, and these chambers have ports 32 formed in the connecting piece 3 at the lowest point thereof for draining oil to the outside of the motor driven compressor.

Referring more specifically to the cylinder supports 10 and parts associated therewith, these cylinder supports 10 support cylinders 33 therein, the bores of the supports 10 forming counterbores 34 when considered with reference to the bores of the cylinder proper 33. The cylinders 33 are held in place by having formed thereon flanges 35. Bolts 36 clamp heads 37 to the supports 10, at the same time clamping the flange 35 between the heads 37 and the supports 10 in recesses in the supports 10 provided for that purpose. The cylinders 33 are provided with puppet valve seats 38 for puppet valves 39, having their stems 40 supported by passing through bores in the heads 37. These stems 40 extend into pots 41 formed in the outer side of the heads 37 and have a portion thereof threaded for fastening thereto plungers 42 fitting the pots 41. Caps 43 close the outer end of the pots 41 and springs 44, within the pots 41, have their one end acting against the plungers 42, and their other end reacting against the caps 43, tending at all times to force the valves 39 to their seats 38.

Sleeves 45 fit within the supports 10 and are connected to cranks or eccentrics 46 by means of eccentric rods 47, these being pivoted to the sleeve by pins 48. The sleeves 45, see Fig. 2, have extensions 49 at the lower side of their crank case ends, coacting with guide grooves 50 formed in the crank case 2. On the exterior, and near their opposite ends, are formed oil packing grooves 51. These sleeves 45 are equal in thickness 55 with the cylinders 33, so that when the sleeves abut with their ends the open ends of the cylinders 33, the interior of the sleeves 45 will form with the interior of the cylinders 33 a continuous cylindrical space. Pistons 52 fit within the sleeves 45 and also within the cylinders 33 and have the usual spring packing rings 53. The pistons 52 are connected by pins 54 to connecting rods 55, and these in turn are connected to cranks 56 of the cranked armature shaft 20. The

pins 54 are held in place in the pistons 52 by locking screws 57 screwed through the piston and projecting into grooves 58 formed in the pins 54. The cranks or eccentrics 46 have an angular advance of about 45 degrees with respect to their corresponding cranks 56. Inlet ports 59, 59, are formed in the supports 10 and connect with the inlet conduit or chamber 15 which is completed by a plate 60 bolted to the lower connecting portion 14. This inlet conduit or chamber 15 has an inlet opening 61 leading thereto formed in the plate 60 for an inlet pipe 62 which may be led to any convenient point for supply of atmospheric air through the usual strainer, not shown. A discharge pipe 63 communicates with the discharge conduit 140.

A supporting lug 64 is formed at the lower part of the crank case 2 and extends to the lowest level of the motor frame 1. This supporting lug forms a support for the crank case 2 when otherwise blocked up, at such times as the motor frame 1 may be disconnected from the motor driven compressor.

A plug 65 closes an opening into the crank case 2 for supplying lubricating oil thereto, of which an abundant supply is maintained in the bottom of the chamber therein. A drain plug 66 closes an opening into the lowest part of the crank case 2. The lowest portion of the crank case 2 takes the form of a pocket 67. A similar pocket 68 is formed in the highest portion of the crank case 2 opposite the pocket 67. A vent 69 connects from the atmosphere into the crank case 2 at the upper end of the pocket 68. This vent is closed by a suitable screen, not specifically indicated. Strengthening ribs 70, 70, 70, 70, are formed on the crank case 2 extending to the edge of the flange formed thereon. A door 71 closes an opening in the motor cover plate 8.

Oil conduits 72 are formed in the supports 10 and connect with passages 73 formed in the crank case 2 draining from a pocket 74 formed in the upper part of the crank case 2. These conduits 72 terminate in the bores of the supports 10. The oil conduits 72 are formed by intersecting passages, one of which leads to the atmosphere but is stopped off by a plug 720 in the bottom of which a screw 721 is threaded supporting a series of felt washers 722 directly opposite the remaining intersecting passage of the conduit 72.

During the operation of the motor driven compressor, and considering the beginning of the stroke of the piston as shown in the first compressor in section in Fig. 1, the sleeve 45 has already performed a portion of its compressing stroke and is partly covering the inlet ports 59. The sleeve 45 is therefore constantly accelerating in speed

while the piston 52 is moving very slowly, the direction of piston motion being indicated in this figure by arrows. The middle compressor shown in this figure is next in 5 advance of the one just considered and shows the sleeve 45 as having passed the inlet ports 59 and about to complete its stroke by abutting with its end the end of the cylinder 33. The piston 52 in this case 10 is shown as having more than half completed its stroke. As it continues in its stroke its advancing face passes into cylinder 33 at the time of abutment between the sleeve 45 and the cylinder 33. This insures 15 that the air compressed by the sleeve 45 between its end and the end of cylinder 33 will be forced out into the continuous cylindrical space formed within the cylinder 33 and the sleeve 45, and this air will then be carried along by the piston 52 into the cylinder 33 to be further compressed and finally to be forced past the discharge valve 39. There is practically no clearance. As soon 25 as the piston 52 passes the abutting faces of the sleeve 45 and cylinder 33 on its compressing stroke, the sleeve 45 begins its return stroke, but the piston has by this time sealed the cylinder 33 from any back flow of air. A partial vacuum may form during 30 the first part of the receding stroke of the sleeve 45 up to the point where the inlet ports 59 are uncovered. And the same thing may occur in the cylinder 33 during the first part of the receding stroke of the piston 52 up to the time the piston 52 leaves the cylinder 33, but these vacua will only cause a quicker inrush of inlet air. The third compressor shown in section in Fig. 2 shows the sleeve and piston both in receding position, the piston moving much faster 35 than the sleeve so that at the end of its receding stroke the piston will be in position with reference to the sleeve as best shown in the first compressor in section in Fig. 1. The cycle of operations just described will 40 then be repeated. When the discharge valve 39 is forced open by the compression of air in front of it in the cylinder 33, it causes its plunger 42 to compress air in the pot 41 and also to compress the spring 44 therein, both 45 of these compressions tending to return the valve 39 quickly to its seat the instant the piston commences its receding stroke. The air confined on the valve side of the plunger 42 will serve as a cushion to avoid shock 50 in the seating of the valve 39.

As the motor driven compressor operates, the moving parts in the crank chamber will dip into the oil in the bottom thereof and splash same in all directions. The oil will fill the pocket 74 and will flow therefrom through the passage 73 and the conduit 72 to lubricate the sleeve 45 and the piston 52. During its passage through the conduit 72 it will be filtered by the felt washers 722.

The pin 54 will be lubricated directly from the splash of oil. The pocket 27 will also be filled by the splashing of the oil therein, from which the oil will drain through the port 25 and through the sleeve 26 to the 70 middle of the main bearing of the shaft 20. From this point the oil will drain in one direction directly back to the chamber of the crank case 2, and in the other direction to the groove 28 in the sleeve 26, and from 75 thence through the conduit 29 in the connecting piece 3 directly back into the chamber in the crank case 2.

It will be seen that the sleeve has three separate functions; first, it serves as a valve 80 for opening and closing the inlet ports 59; second, it serves as a piston in compressing air in the counterbore 34; third, it serves as a continuation of cylinder 33 for the piston 52. It should be noted that the support 10 85 need not necessarily be atmospherically tight except at the counterbore portion 34 serving as a cylinder for the sleeve 45 when the sleeve is operating its piston function, but it is formed atmospherically tight for 90 the purpose of preventing the escape of oil, especially that supplied through the conduit 72 to the upper part of the sleeve 45. It should also be noted that the heads 37 95 are formed with conduits which connect the space beyond the puppet valve to the common discharge conduit on the supports 10. This construction will permit of the dismantling of the heads and cylinders without disturbing the piping connections. 100

It should be understood that it is not desired to be limited to the exact details of construction shown and described, for obvious modifications will occur to a person skilled in the art. 105

It is claimed and desired to secure by Letters Patent,—

1. In a compressor, the combination of a cylinder having a bore, a reciprocable sleeve having a bore continuous with the 110 bore of said cylinder, and a piston sliding within said cylinder and sleeve.

2. In a compressor, the combination of a cylinder having a bore, a sleeve having a bore and reciprocable to abut the end of 115 said cylinder, and a piston reciprocable within the bores of said cylinder and sleeve.

3. In a compressor, the combination of a cylinder, a sleeve movable to abut with its end the end of said cylinder, a piston movable within said cylinder and sleeve, and 120 connections whereby said piston face passes said abutting ends at the time of abutment.

4. In a compressor, the combination of a cylinder, a piston reciprocable into and out of said cylinder, and a sleeve fitting said piston and reciprocable to abut the end of 125 said cylinder at the time said piston enters said cylinder.

5. In a compressor, the combination of a 130

4
cylinder having a support forming a counterbore, a piston reciprocable into and out of said cylinder, and a sleeve fitting said piston and reciprocable into and out of said counterbore to abut the end of said cylinder at the time said piston enters said cylinder.

6. In a compressor, the combination of a motor, a motor shaft, and a compressor having a reciprocable valve-piston-cylinder sleeve direct connected to said shaft, said sleeve during at least a portion of its reciprocation serving to compress elastic fluid.

15. 7. In combination, a cylinder having a bore, a reciprocable imperforate valve-piston-cylinder sleeve having a bore continuous with said cylinder bore, and a piston sliding within the bores of said cylinder and sleeve.

20. 8. In combination, a cylinder having a bore, an imperforate valve-piston-cylinder sleeve having a bore, said sleeve being reciprocable to abut an end of said cylinder, and a piston reciprocable within the bores of said cylinder and sleeve.

25. 9. In a compressor, the combination of a crank case having an opening therein, a removable cylinder, spaced from said crank case, an atmospherically tight support connecting said cylinder to said crank case at said opening, parts operating within said cylinder and support, and means for supplying oil to said parts.

30. 10. In a compressor, the combination of a crank case having an opening therein, a series of cylinder supports, a base plate integral with said supports and bolted to said case at said opening therein, connecting portions integral with said supports and extending laterally along opposite sides of said series and forming inlet and discharge chambers respectively, and heads bolted to said supports.

35. 11. The combination of a support, a cylinder snugly fitting but removable from said support, said cylinder forming a puppet valve seat, a puppet valve for said seat, and a head for said support clamping said cylinder in place in said support whereby said 40 seat is on a part independent of said head, and is removable with said cylinder by detachment of said head.

45. 12. In combination, a cylinder having a

bore, a reciprocable imperforate sleeve having a bore concentric with said cylinder bore, 55 and a piston sliding within and coacting directly with the bores of said cylinder and sleeve.

13. In a compressor, the combination of a motor, a motor shaft, a compressor having a reciprocable valve-piston-cylinder sleeve direct connected to said shaft, and a piston reciprocable within said sleeve, said sleeve during its reciprocation serving to positively displace fluid for compression by 65 said piston.

14. In a compressor, a crank case, a cylinder spaced from and open-ended toward the crank case, a piston entering and entirely leaving said cylinder during normal operation and a reciprocable valve-piston-cylinder sleeve surrounding said piston and movable to abut said cylinder.

15. In combination, a cylinder having a bore, and a reciprocable imperforate valve-piston-cylinder sleeve having a bore continuous with said cylinder bore.

16. In combination, a cylinder having a bore, a reciprocable imperforate sleeve having a bore concentric with said cylinder 80 bore, and means coacting directly with the bores of said cylinder and sleeve.

17. In combination, a cylinder having a bore, a reciprocable imperforate valve-piston-cylinder sleeve having a bore concentric 85 with said cylinder bore, and means coacting directly with the bores of said cylinder and sleeve.

18. In combination, a cylinder having a bore, a bored imperforate sleeve reciprocable to abut an end of said cylinder, and means coacting directly with the bores of 90 said cylinder and sleeve.

19. In combination, a cylinder having a bore and a reciprocable imperforate valve-piston-cylinder sleeve having a bore, said 95 sleeve having an end surface engageable during its reciprocation with an end of said cylinder.

In testimony whereof, the signature of 100 the inventor is affixed hereto in the presence of two witnesses.

G. F. DEWEIN.

It is hereby certified that in Letters Patent No. 1,172,581, granted February 22, 1916, upon the application of Herbert W. Cheney, of Milwaukee, Wisconsin, for an improvement in "Motor-Driven Compressors," errors appear in the printed specification requiring correction as follows: Page 4, line 28, claim 9, after the word "cylinder" strike out the comma; same page, line 50, claim 11, after the word "head" strike out the comma; and that the said Letters Patent should be read with these corrections therein that the same may conform to the record of the case in the Patent Office.

Signed and sealed this 14th day of March, A. D., 1916.

[SEAL.]

J. T. NEWTON,

Acting Commissioner of Patents.
